UNITED STATES PATENT OFFICE.

CHARLES M. HILLIKER AND NATHAN SALOMONSKY, OF NEW YORK, N. Y.

SPARKING DEVICE.

1,125,097.

Specification of Letters Patent.

Patented Jan. 19, 1915.

Application filed February 23, 1912. Serial No. 750,732.

To all whom it may concern:

Be it known that we, CHARLES M. HILLIKER and NATHAN SALOMONSKY, citizens of the United States of America, both residing at the city of New York, in the county and State of New York, have invented certain new and useful Improvements in Sparking Devices, of which the following is a specification.

10 Our invention relates to spark plugs adapted to ignite vaporized gasolene and other materials, usually for the purpose of producing that power which results from the explosion of a quantity of gas, but we do not limit it to a combination including the cylinder of the usual gas motor, since it is capable of other uses, though we have so designed it that it may be used with such a motor with great acceptability.

20 One feature consists in providing for a double or single spark gap and another in so arranging the instrumentalities that the sparking points or terminals may be readily cleaned.

25 Figure 1, is a side view of one form of our device. Fig. 2 is a central vertical sectional view of said device. Figs. 3, 4, 5, are diagrammatic views of the points in different situations. Fig. 6 represents a modification.

30 Fig. 7 is a vertical sectional view of a plug in which the bridge piece is fixed and the terminal may be rotated. Fig. 8 is an under face view of the plug of Fig. 7.

1 represents a hollow plug provided with 35 angular faces 2 to accommodate a wrench and a threaded portion 3 adapted to turn into an opening in a cylinder or other device to which it is desired to attach the plug. Plug 1, has a central bore 4, preferably 40 shouldered at 5. In that bore, we locate an insulator block 6, usually a porcelain cylinder provided with an integral collar 7 adapted to rest on shoulder 5, and be held in place by a follower 8, threaded into plug 45 1, and provided with a milled periphery 9 beyond the line of plug 1. This follower also secures the asbestos packing 10, in position between its lower edge and the shoulder 5.

50 The insulator block 6, is bored longitudinally at 11 and 12, and its upper end is preferably stepped as shown to provide different levels for the attachments which are to occupy the bores 11 and 12. Bore 11 is 55 preferably occupied by a conductive terminal 14, extending through it, threaded at the

outer end and there provided with a nut 15, to act as a binding post for the one circuit wire. At the other end it forms an electrode or point 16, preferably L shaped, and shouldered at 17 to support an asbestos packing ring 18, between the shoulder and a recess 19 sunk into the block 6. The other bore 12, is occupied by a rod 20, conductive or not at pleasure, and at its lower end we 60 construct a bridge piece 21, of conductive metal, shouldered at 22 and holding a ring of asbestos packing 23 up against the wall of a second recess 24, sunk in the block 6, concentrically with bore 12. The second 70 electrode 25, extends downward from the plug 1 or, it may be an independent conductive piece extending up through the plug to a place convenient for the attachment of the other circuit wire. Its lower end 26 is also 75 preferably L shaped with the toe projecting toward the toe of the other electrode.

At the upper end of rod 20, we mount a handle 27, with an enlarged end, which is counter-bored to accommodate a coil spring 80 28 set within a counterbore and surrounding rod 20, its stress being arranged to hold the shoulder of rod 20 against the packing ring and at the same time to create sufficient friction to hold said rod 20 at any angle of 85 oscillation to which it may be turned. The bridge piece, on this rod 20, is the feature which enables us to accomplish our purpose in a very simple manner. Measured at one diameter, it is wide enough to reach from 90 one toe piece to the other one. Consequently by turning it so that that particular diameter crosses a line drawn from one toe piece to the other, we can readily brush, rub or clean off any smut or soot which has collected on the spark points or poles, and keep them clean and always ready for action. To assist in this action, the pole pieces, terminals or electrodes, 16 and 26, may be slightly 95 resilient (or the bridge ends) and the 100 bridge, at the given diameter, a little longer than the intervening space from 16 to 26. Measured through another diameter (see Fig. 4) the bridge will span the distance from its pivot to one of the toe pieces, but 105 not to the other. Consequently, when properly connected to a source of electrical power, there will be a spark at the gap from the free end of the bridge to the toe piece not in contact with it. Measured through a 110 third diameter, (see Fig. 5) the bridge piece will not reach from its pivot to either toe

piece, but the separation is such that the spark will itself bridge the intervals, thus producing a double spark gap, with all the advantages attendant upon such a production.

The form we prefer for accomplishing the results noted, is that shown in Figs. 1 and 2, in which the bridge piece, in cross section, is somewhat trapezoidal in form, or rather 10 resembling a circle of a diameter as great as the separation of the toe pieces one from the other, from which unequal segments have been cut, leaving two preferably straight sides which are less distant from the center 15 than the distance from that center to the toe pieces, the sides being joined by curved portions of the original circle, one of which portions is greater than the other. With a bridge piece of such form, the shifting to 20 the various positions is a very simple matter. By turning the handle to the position of Fig. 3, the bridge will be caused to make contact with both toe pieces and a slight vibration will effect their cleaning. By turning 25 the handle to the position of Fig. 4, the end of the bridge with the short curve will separate from the toe piece 16 while the part with the longer curve will maintain its contact with the toe piece 26 and a single gap 30 arrangement will be produced. The friction maintained by spring 28 will hold the bridge in either of the positions to which it is turned. Substantially similar results may be attained by the use of the form shown in 35 Fig. 6. The bridge piece of that figure, though preferably integral, is constructed as though it consisted of three bridge pieces, one above another, arranged in any order desired, preferably with the shortest piece 40 at the bottom, the longest next above and the one of intermediate length at the top, the handle being provided with a cam, 30.

When the handle is turned to one position, the rod will be brought to such a position that the long bridge contacts with the toe pieces, and, as before, its oscillation will clean the points. When the handle is turned to another position, the upper bridge will be at the level of the toe pieces and the 50 single gap arrangement will be instituted, but if the handle be turned to the position shown in Fig. 6, the short bridge will be brought to the level of the points and the double gap arrangement will result.

The combination is one of great simplicity and nevertheless of great capacities. The idea of arranging a bridge to secure a double spark is not limited to the arrangement of Figs. 1-5. In Figs. 7 and 8, we show another style. In this form, one terminal 16 becomes the movable part and an independent bridge 31 is seated in the porcelain block 3. Then we provide two projections or toe pieces 26^a, 26^b, extending from plug 1, 26^a being usually longer than 26^b and we con-

struct the rod of terminal 16^a so that it may turn in the porcelain block, and secure a handle directly to said rod. The terminal 16^a is likewise provided with two toe pieces so arranged that upon turning the rod to 70 one radial mark, it will contact with toe piece 26^a but upon turning it to another radial mark it will contact with toe piece of bridge piece 31. It is thus rendered capable of cleaning those toe pieces. Not only so, 75 but when set so that only a slight, gap exists between terminal 16^a and bridge 31, the gap between bridge 31 and 26^b being also slight there will be a double gap spark from terminal 16^a to bridge 31 and from bridge 80 31 to toe piece 26^b, the distance from 16^a to terminal 26^b being then so great that there is no likelihood of any spark between them. When the terminal 16^a is turned so that only a slight gap exists between it and toe piece 85 26^a, then there will be a single gap spark between them, the distance from the terminal 16^a to the bridge 31 being then too great for a spark at that point.

What we claim as our invention and desire to secure by Letters Patent is:—

1. A sparking device composed of a body adapted to be connected with a receptacle for material to be fired, and supporting a bridge of conducting material and two electrodes; one of said parts being oscillatable toward or from another, one electrode and the bridge being insulated from the metal of the plug, and both electrodes being provided with circuit connections, said bridge piece being arranged between the electrodes and adapted as described to permit a double gap spark to be created between it and the electrodes when the parts are in one position, but only a single spark when they are 105 in a different relative position, all substantially as set forth.

2. A sparking device composed of a body adapted to be connected with a receptacle for material to be fired, and supporting a 110 bridge of conducting material and two electrodes; one of said three supported parts being oscillatable toward or from another, one electrode and the bridge being insulated from the metal of the plug, and both electrodes being provided with circuit connections, said oscillatory part being provided with toe pieces, adapted as described to contact with the adjacent sparking points of the other two of said three supported devices during some part of an oscillation, said bridge piece being arranged between the electrodes and the oscillating part being adapted as described, to permit a double gap spark to be created between itself and 125 the other two of said devices when the parts are in one position, but only a single spark when they are in a different relative position, all substantially as set forth.

3. A sparking device, composed of a body 130

adapted to be connected with a receptacle for material to be fired, two electrodes connected therewith, but insulated one from the other, one of them being also insulated from the metal of the plug and both of them being provided with circuit connections, sparking points supported by said electrodes, and a movable bridge piece of conducting material arranged between them, of such dimensions, that in one relative position it reaches from one sparking point to the other, but when moved from such position it will reach to one point but not to the other, all substantially as set forth.

15 4. A sparking device composed of a body adapted to be connected with a receptacle for material to be fired and supporting two electrodes connected therewith, but insulated one from the other, one of them being also insulated from the metal of the plug and both of them being provided with circuit connections, sparking points supported by said electrodes, and a movable bridge piece of conducting material arranged between them, of such dimensions, that in one position it reaches from one sparking point to the other but when moved from such relative position to another it will reach to one point but not the other, and in a third position will reach neither, all substantially as set forth.

5 5. A sparking device, composed of a body adapted to be connected with a receptacle for material to be fired, and supporting two electrodes connected therewith, but insulated one from the other, one of them being also insulated from the metal of the plug, and both of them being provided with circuit connections, sparking points supported by said electrodes, and a movable bridge piece of conducting material arranged between them, of such dimensions that in one position it will reach to one point but not the other and in another relative position it will reach to neither point, all substantially as set forth.

6. A sparking device, composed of a body adapted to be connected with a receptacle for material to be fired, and supporting two electrodes connected therewith, but insulated one from the other, one of them being also insulated from the metal of the plug and both of them being provided with circuit connections, sparking points supported by said electrodes, and a movable bridge piece of conducting material arranged between them, and supported upon an oscillatory rod, its radial measurements on one diametric line, normally in the plane of the sparking points, being respectively as great as the distances from its axis to the respective points, together with means for oscillating it upon its axis, all substantially as set forth.

65 7. A sparking device, composed of a body

adapted to be connected with a receptacle for material to be fired, and supporting two electrodes, connected therewith, but insulated one from the other, one of them being also insulated from the metal of the plug and both of them being provided with circuit connections, sparking points supported by said electrodes, and a movable bridge piece of conducting material arranged between them, and supported upon an oscillatory rod, its radial measurements on one diametric line, normally in the plane of the sparking points, being respectively as great as the distances from its axis to the respective points, and upon another diametric line in said plane, being respectively, one as great as the distance from its axis to one sparking point and the other less than the distance from its axis to one sparking point, together with means for oscillating it upon its axis, all substantially as set forth.

8. A sparking device, composed of a body adapted to be connected with a receptacle for material to be fired, and supporting two electrodes connected therewith, but insulated one from the other, one of them being also insulated from the metal of the plug and both of them being provided with circuit connections, sparking points supported by said electrodes, a movable bridge piece of conducting material, arranged between them and supported upon an oscillatory rod, its radial measurements on one diametric line, normally in the plane of the sparking points, being respectively as great as the distances from its axis to the respective points, and upon another diametric line in said plane, being respectively, one as great as the distance from its axis to one sparking point and the other less than the distance from its axis to one sparking point, and upon a third diametric line in said plane, being respectively less than the distance from its axis to the respective sparking points, together with means for oscillating it upon its axis, all substantially as set forth.

9. A sparking device, composed of a body adapted to be connected with a receptacle for material to be fired, and supporting two electrodes connected therewith, but insulated one from the other, one of them being also insulated from the metal of the plug and both of them being provided with circuit connections, sparking points supported by said electrodes, and a movable bridge piece of conducting material, arranged between them, and supported upon an oscillatory rod, its radial measurements, on one diametric line, normally in the plane of the sparking points, being respectively, one as great as the distance from its axis to one sparking point and the other less than the distance from its axis to one sparking point, and upon another diametric line in said

- plane, each of said measurements less than the distance from its axis to a sparking point, together with means for oscillating said bridge piece, all substantially as set forth.
10. A sparking device composed of a metal plug, an insulating block seated in said plug, a sparking point supported on an arm extending from said plug, a sparking point supported on a rod extending through said block, a bridge piece supported on a rod extending through said block and adapted to oscillate therein, a handle secured to the outer part of said bridge rod, said bridge piece of conducting material in section, in the plane of the sparking points, being as long from its axis in one line as the spaces between the points, as long, on another line, in said plane, as the space from its axis to 15 one adjacent sparking point, but not to the other and less upon another line in that plane, than the distance from its axis to the adjacent sparking points, all substantially as set forth.
20. 11. A sparking device composed of a 25

metal plug, an insulator block seated in said plug and stepped at the outer end, a sparking point supported on an arm extending from said plug, a sparking point supported on a rod extending through said block, a bridge piece of conducting material supported on a rod extending through said block and adapted to oscillate therein, a handle secured to the outer part of said bridge rod, at the line of a step other than 30 that from which the terminal rod extends, said bridge piece in section, in the plane of the sparking points, being as long from its axis in one line as the spaces between the points, and shorter on another line, all substantially as set forth.

In testimony whereof, we have signed our names to this specification in the presence of two subscribing witnesses, this 22nd day of July 1912.
